UNITED STATES PATENT OFFICE

2,165,806

ELECTRIC DISCHARGE DEVICE

George A. Morton, Haddon Heights, and Leslie E. Flory, Oaklyn, N. J., assignors to Radio Corporation of America, a corporation of Delaware

Application February 28, 1935, Serial No. 8,630
Renewed May 12, 1937

5 Claims. (Cl. 250—166)

Our invention relates to electric discharge devices and more particularly to devices of the type wherein amplification of a primary electron stream, such, for example, as is emitted from a thermionic cathode or from a photo-sensitive surface exposed to light, is accomplished through utilization of the phenomenon of secondary emission.

If an electrode is subjected to electron bombardment, it will emit secondary electrons. The ratio of the number of secondary electrons to the number of primary electrons depends, in part, upon the character of the bombarded surface and upon the potential difference between the surface and the source of the electrons. This ratio can be made considerably greater than unity. For example, a ratio of three or more secondary electrons to one impinging electron is readily obtainable with metallic surfaces treated in known ways and subjected to discharges at potentials of 300 to 400 volts. Since the emitted electrons exceed the impinging electrons in number, the electrodes emitting them, hereinafter, will usually be referred to as "multiplying" electrodes.

If the secondary electron current, in turn, is caused to impinge with sufficient velocity upon a further electrode with a suitably treated surface, the ratio of secondary emission from the second multiplying electrode may also be greater than unity. Hence, one is able to obtain with "n" multiplying electrodes in cascade, for example, an amplification of the original or primary electron current equivalent to the amplification per electrode raised to the n th power. A million-fold amplification may be obtained in a single device.

Prior art devices, wherein the phenomenon of secondary emission is utilized for amplification, have proved to be unreliable and inefficient, principally because of incomplete and uncertain control and utilization of the secondary electron streams. For example, in the operation of a device constructed according to French Patent 582,428 (Dapsence et al.), the same electrostatic fields are utilized for electron acceleration and for determining the paths described by the primary and secondary electrons. It has been found that, in general, it is very difficult to control the paths of the electrons in a tube of that type in such manner as to cause all of the electrons from any one source to fall upon the desired target.

Another disadvantage of previous electron multipliers, of types exemplified by the French

patent, resides in the fact that the field in the neighborhood of each multiplying electrode, which serves to draw off the secondary electrons, must necessarily be weak. Because of the small magnitude of the field, it is impossible to draw large currents from those electrodes. An attempt to overcome this defect by increasing the potential of the succeeding electrode, with the object of increasing the accelerating field in the neighborhood of the preceding multiplying electrode, generally results in a decreased gain since some of the primary electrons which would normally strike the preceding multiplying electrode are drawn past it to one of the following electrodes. As a consequence, because of the space-charge limitation of current, it is impossible to maintain linearity between the input excitation or the current from the primary source, and the output current, except for extremely weak output currents.

It is, accordingly, an object of our invention to provide an electric discharge device, utilizing secondary electron emission, wherein maximum gain per stage is obtained and linearity may be obtained between input excitation and output current.

Another object of our invention is to provide an amplifier or electron multiplier of the secondary electron emission type in which the secondary electron stream from each emitter is concentrated and is directed accurately to the desired target, and interference between the various secondary electron streams is minimized.

Another object of our invention is to provide an amplifier or electron multiplier wherein there is practically no loss of secondary electrons and in which the best conditions for amplification, or other desired results, can easily be obtained by external potential adjustments.

Another object of our invention is to provide an amplifier or electron multiplier that is efficient and reliable in operation and in which the amplification obtainable is very great as compared with the amplification obtainable with a thermionic amplifier of usual type.

Another object of our invention is to provide a device of the type described that may be used for substantially any purpose for which thermionic tubes of present types are used, such, for example, as an amplifier, a demodulator, an oscillator, a combined oscillator and demodulator, etc.

Another object of our invention is to provide a combined phototube and amplifier that shall be responsive to the very highest frequencies en-

countered in television transmitting apparatus. A still further and more specific object of our invention is to provide a device of the type described that lends itself readily to mass production methods.

The foregoing objects and other objects ancillary thereto we prefer to accomplish by the provision of separate electrostatic fields for the production of secondary electrons from one electrode and the focusing of the electrons upon the next succeeding electrode. In particular, in a preferred embodiment of our invention we cause electrons emitted from a primary source, either photo-electric or thermionic in character, to impinge upon a surface capable of secondary emission at a velocity sufficiently high to produce secondary emission having a ratio greater than unity to the primary electron stream. Through utilization of an electron lens system, the secondary electron stream thus produced is directed against another similar surface at a still higher positive potential whereat further secondary electrons are produced. In each case electron lenses are made use of for the purpose of concentrating and directing the primary electrons toward the first secondary emitter, the secondary electrons from the first emitter toward the second emitter and so on. This process may be repeated a number of times within the same container and the final greatly amplified stream of secondary electrons is collected by an output electrode.

More specifically stated, a preferred embodiment of our invention is constituted by an evacuated zig-zag-shape container wherein are supported a plurality of successively disposed electrodes and the inner walls of which, between the electrodes, are provided with conductive coatings which, when supplied with proper potentials, function as electron lenses.

As will be pointed out hereinafter, the zig-zag shape of the container is not absolutely essential but it readily lends itself to manufacturing methods and it has been found most convenient for experimental purposes.

Further, in accordance with our invention, each of the successive electrodes and each of the coatings, going to make up the electron lenses, is provided with a lead extending exteriorly of the container, by means of which proper potentials may be applied thereto in operation.

Because of the fact that we utilize electron lenses for the purpose of concentrating and directing electrons from place to place in our improved device, we are enabled to employ it in apparatus wherein the presence of electromagnetic focusing fields would be detrimental.

The novel features which we believe to be characteristic of our invention are set forth with particularity in the appended claims. Our invention itself, however, both as to its organization and method of operation will best be understood by reference to the following description taken in connection with the accompanying drawings, in which:

Figure 1 is a view in perspective of a preferred embodiment of our invention, portions of the wall being broken away to more clearly disclose the electrode structure and disposition.

Fig. 2 is a diagrammatic view of the device shown in Fig. 1, exemplifying the manner in which the several electrodes are energized when the device is utilized for certain of the purposes to which it is adapted.

Fig. 3 is a diagrammatic view of an alternative embodiment of our invention, and

Fig. 4 is a diagrammatic view exemplifying the utilization of our electric discharge device as a "degenerative" amplifier.

Referring now to Fig. 1 of the drawings, an electron discharge device, constructed according to our invention, may be constituted by an N-shape evacuated container 1 in one end of which is disposed an electron source constituted by a photo-sensitive cathode 3 and in the other end of which is mounted an output electrode 5. It is, of course, to be understood that the cathode is shown mainly by way of example, since the electrons can be introduced into the device from a source exterior thereof. A multiplying electrode 7 having a surface capable of secondary emission is mounted within the container at the junction between the first leg 9 of the container and the connecting portion 11 between it and the second leg 13, and a similar multiplying electrode 15 is mounted within the container at the junction between the connecting portion and the second leg. Each multiplying electrode is so disposed that the axes of the leg and connecting portion adjacent thereto make substantially equal angles therewith.

For the purpose of concentrating accelerating and directing electrons from the cathode 3 toward the first multiplying electrode 7, an electron-lens is disposed therebetween. This lens is constituted by a foraminous cylinder 17 adjacent to the cathode and a conductive coating 19 upon the inner wall of the container leg adjacent to the first multiplying electrode, to each of which appropriate potentials may be applied.

As will be hereinafter shown more in detail, primary electrons emitted from the cathode are focused and directed toward the first multiplying electrode 7 by means of the electron lens just mentioned and thereby cause the profuse emission of secondary electrons.

For the purpose of removing the secondary electrons and of giving them an initial velocity toward the second multiplying electrode 15, we may interpose, within the connecting member 11 of the tube, an accelerating screen element 21 to which a positive potential may be applied. In order that the secondary electrons from the first multiplying electrode may be further accelerated and concentrated upon the second multiplying electrode 15, we interpose a second electron lens, constituted by a plurality of spaced apart conductive wall coatings 23 and 25, between the first multiplying electrode and the second multiplying electrode. To these coatings the proper potentials may also be applied, as will later be shown.

The screen is not an absolutely essential of our improved device. If it is omitted, the first element of the electron lens adjacent to the multiplying electrode, if maintained at a higher potential, will serve to remove the secondary electrons and direct them toward the next multiplying electrode.

If desirable, the second leg 13 of the container may be replaced by a second connecting tube provided with an additional accelerating screen, 65 analogous to the screen element 21, as well as suitable electron-lens-forming elements, and the secondary electrons from the second emitter may again be concentrated and directed toward a third multiplying electrode. For the purpose of 70 simplifying the drawings, however, we have omitted further multiplying electrodes and have merely shown the output electrode 5 as adjacent to the secondary emitter. We wish it also to be clearly understood that the elements constitut-

ing the electron-lenses may be disposed exteriorly of the container without departing, in any way, from the spirit of our invention.

In the device as actually constructed, the photo-sensitive cathode is constituted by a disc of pure silver about three-quarters of an inch in diameter and ten-thousandths of an inch thick. The foraminous cylinder is made of nickel 32 mesh screen, which material was also utilized for the accelerating screen electrode. The multiplying electrodes or targets are also of pure silver, substantially one inch in diameter and ten-thousandths of an inch thick. The output electrode is preferably made of tantalum or an analogous metal three-quarters of an inch in diameter and five-thousandths of an inch thick.

Referring now to Fig. 2 of the drawings, in the operation of the device the photo-sensitive electrode, the several multiplying electrodes, the accelerating screen and the electron-lens elements may be supplied with suitable potentials from any available source of direct current. This source is exemplified in the drawings by a potential divider 26 to the negative terminal of which is connected the cathode 3 and to the positive terminal of which, through an output resistor 28, is connected the output electrode 5. From an inspection of Fig. 2, it will be noted that, starting with the cathode, each element is connected to a successively more positive point upon the potential divider. Such mode of connection we have found to be advantageous but it is not to be inferred from the drawings that it is obligatory, since it is entirely possible to maintain each multiplying electrode at the lower potential of the lens element next adjacent thereto and accelerating screen may also be omitted. Alternatively, the cylinder 17 may be maintained at the potential of the cathode 3, if desired.

Since the foraminous cylinder 17 is an element of the first electron-lens adjacent to the cathode, it, of course, could be replaced by a conductive coating on the inner wall of the tube. The form shown, however, is advantageous in that it permits the ingress of light from any suitable source. This source might be modulated by a moving photographic sound record or it might be any other source of light corresponding to the fluctuations of which an amplified electric current is desired.

In order that our disclosure may be complete, we shall now give the sequence of operations in manufacturing the actual device, shown in Fig. 1, of the drawings.

The glass envelope was first fabricated in the form shown, the ends of the legs and the junctions between the legs being left open in order to permit the sealing therein of the respective electrode-supporting presses.

After the glass blank was prepared, the positions of the metallic coatings on the glass were marked off and, on the inside of the blank, was deposited a commercially available platinizing solution following the marks previously made. The whole blank was then heated to approximately 400° centigrade in order to reduce this platinizing solution to metallic platinum. The electrodes, previously described, were mounted on the wires of the glass presses which were then sealed in place. The tube was sealed to a high vacuum system by means of a tubulation (not shown), through which the tube could be evacuated. An appendage (not shown) containing pellets of a caesium compound, such as caesium chromate, and a reducing agent, such as alumini-

um powder or silicon powder, was sealed onto the tube by means of another tubulation (not shown) through which the caesium from the pellets could be admitted to the main body of the tube.

The tube was then baked at 450° centigrade, being evacuated at the same time. The bake continued for approximately thirty minutes after the oven reached the final temperature. After the baking, the tube was cooled and a small amount of pure oxygen was introduced into it at a pressure of approximately 1 mm. of mercury. The cathode and multiplying electrodes were next oxidized by passing an electrical discharge from these elements to some other element in the tube until the electrode surfaces acquired a bluish-green tinge. The oxygen was then pumped out and the pellets of caesium compound and reducer were heated sufficiently to start the reaction which yields metallic caesium. The metallic caesium was driven, by means of heating the appendage, into the main body of the tube. The tube was once more baked at 200° centigrade for approximately ten minutes and allowed to cool. The caesium appendage was then sealed off the tube and the tube sealed off the vacuum system.

It might be thought that the caesium would be deposited upon the lens-elements and the electrodes other than those which are intended for primary or secondary emission. Such is undoubtedly the case, but, by reason of the greater affinity of caesium for an oxide, particularly silver oxide, when the tube was heated in the final heating, most of the caesium was driven off the other elements and was taken up by the oxidized silver electrodes. The caesium forms a chemical compound with the silver oxide which is reasonably stable, although the actual chemical reaction that takes place is not definitely and accurately known.

From the foregoing description of the device shown in Fig. 1 of the drawings, it is, of course, possible to infer that the zig-zag shape is necessary. Such is not the case, however, since the elements themselves may be arranged in a zig-zag path within a cylindrical container. An alternative device of such type is exemplified by Fig. 3 of the drawings, wherein elements corresponding to those shown in Fig. 1 are similarly designated.

It should also be understood that we are not limited to the use of a photosensitive cathode, since it lies within the scope of our invention to replace it by any suitable electron source, such as one of the thermionic type, and to provide one or more grids for the purpose of suitably controlling the electron emission. The manner in which a controllable thermionic source could be mounted in the container in lieu of the photo-sensitive cathode 3 will be perfectly apparent to those skilled in the art and no necessity is seen for illustrating it. If further information, however, is desirable, attention is directed toward the copending application, Serial No. 4,049, filed January 30, 1935, in the name of Louis Malter, and assigned to Radio Corporation of America.

Referring once more to Fig. 2 of the drawings, when light, steady or fluctuating in character, falls upon the photo-sensitive cathode 3, primary electrons are emitted therefrom in random directions. By reason of the positive potential applied to the first multiplying electrode, the primary electrons are accelerated toward it. In order to make certain that substantially all of the

primary electrons reach the first multiplying electrode, the foraminous cylinder 17 and the first interior coating 19 are maintained at successive-
 5 ly higher positive potentials with respect to the cathode. In such case, the space between the cylinder and the coating function as converging electron-lens to cause the random secondary electrons to be focused upon a definite portion of the first accelerating electrode. The secondary elec-
 10 trons emitted from said electrode are given an initial acceleration toward the second multiplying electrode by means of the interposed screen 21. They are directed and focused upon the second multiplying electrode 15 by means of the
 15 second electron-lens constituted by the intermediate coatings 23 and 25, in the same manner as described in connection with the primary electrons. Upon reaching the second multiplying electrode the secondary electrons drive out further secondary electrons which are drawn over to the output electrode and give rise to current in the output resistor.

Our improved device, in addition to its capability of providing a fluctuating current in response to a fluctuating light source, is also capable of giving non-linear amplification. That is to say, in either the photosensitive type or the thermionic type, an output current may be obtained which is not directly proportional to input 20 excitation but which follows some other curve. Non-linearity may be, for example, obtained by interposing an impedance device 27 between the potential divider and the first multiplying electrode 7. This impedance device may be a resistor or an inductor having such electrical characteristics that when the current therethrough changes, the potential on the secondary emitting electrode also changes to alter the gain in proportion thereto. An inductor, of course, would be 30 preferable if a characteristic non-linear with respect to frequency is desired.

We have also discovered that our improved device may be so operated as a degenerative amplifier that a variation in the output current therefrom causes a corresponding variation in the primary electron stream in such direction as to oppose the original stream-variation which causes the said output variation.

We have not thoroughly investigated the possibilities of our device in the aforementioned direction but it could probably be used for the purpose of regulating a power supply or for some analogous purpose.

The manner in which our device may be utilized as a degenerative amplifier or as a non-fluctuating source of electrons is exemplified by Fig. 4 of the drawings, wherein elements analogous to those shown in Figs. 1, 2 and 3 are similarly designated.

Referring to Fig. 4, it will be noted that a resistor 29 is interposed between the potential divider 26 and the second multiplying electrode. A similar resistor 31 is interposed between the potential divider and the photosensitive cathode, 65 the two resistors being coupled through a capacitor 33. A signal to be amplified may be applied to the screen element 21A interposed between the second multiplying electrode 15 and the output electrode 5 as, for example, by means of an input element, such as a resistor 35, included between the potential divider and the screen. Assuming that the light which energizes the cathode 3 suffers an undesired momentary increase in intensity, this gives rise to (a) increased photo-emission from the cathode, (b)

increased secondary emission from electrodes 7 and 15 and (c) an increase in the flow of electrons to electrode 15 through resistor 29. The increase in the flow of electrons to electrode 15, through resistor 29, causes an increase in the 10 already positive potential thereon and, since electrode 15 is coupled to the cathode 3 through capacitor 33, this change in voltage will be reflected in an increase in the potential of the cathode. This increase in the potential upon the 15 cathode decreases the potential between the cathode 3 and the first multiplying electrode 7. As a result the primary electrons strike electrode 7 with a lower velocity causing a decrease in the ratio of secondary electrons to primary electrons, and hence a decrease in the number of electrons striking electrode 15. This compensates for the previously described increase in the number of electrons striking electrode 15 due to the undesired momentary increase in the intensity of the 20 light which energizes the cathode. The electron stream, therefore, between the second multiplying electrode 15 and the output electrode 5 is responsive to the input signal only and its magnitude is thus rendered substantially independent 25 of light fluctuations.

If amplification of the controlled secondary electron stream is desired, additional multiplying stages may be interposed between the second multiplying electrode and the output electrode 30 in the manner indicated by Fig. 3.

Obviously, an analogous system could be employed in connection with a device of the thermionic type but since the connections are obvious, no necessity is seen for further illustration.

Our improved device, either of the photosensitive cathode or the thermionic cathode type, is capable of generating sustained oscillations. This may be accomplished through utilization of any of the conventional regeneration circuits 40 which permit of feeding back a portion of the output potential to the input circuit in proper phase.

Sight should not be lost, also, of the fact that our device is capable of use as a demodulator. Such purpose may be accomplished by applying 45 the signal to be demodulated either across the impedance device 27, shown in Fig. 2, or in series therewith.

Many other uses of our device will be apparent to those skilled in the art, such, for example, its use as a combined oscillator-modulator through the application of modulating potentials to one of the targets within the tube while the carrier frequency is applied to the input circuit or while 55 the device is in the self-oscillatory condition. Since it is substantially impossible to list herein all of the possibilities of our improved device, it is to be distinctly understood that our invention is not to be circumscribed by the examples given. 60

By reason of the shape of our improved electric discharge device and the presence of the electron lenses, electrons from any given source are prevented from being driven past their pre-allocated target and are caused to impinge 65 thereon.

Because of the fact that the acceleration of the electrons is produced through the action of an electric field which does not interfere with the focusing action of the electron-lenses, the space 70 charge limitations of prior devices are avoided. The efficiency thus obtained is much greater than where dependence is placed solely upon electrostatic fields between adjacent electrodes for the purpose of both accelerating the electrons 75

and directing them to the secondary emitters. By providing the electron lenses the impinging electron stream is concentrated and directed to the emitting surface and at the same time there 5 may be maintained at the surface an electrostatic potential gradient which is favorable for removing the emitted electrons with maximum efficiency. Substantially no interference or interruption between the high velocity impinging 10 electrons and the low velocity secondary electrons has been observed and it seems highly probable that there is no actual interference between the concentrating fields and the accelerating fields. It follows from the foregoing enumerated facts 15 that in our improved device the output current is not limited by space charges. As a result, the device appears to have no saturation point, the amount of output current which it can provide being only dependent upon the amount of heat 20 which the electrodes can dissipate, upon their resistance to destructive electrostatic forces, the potentials applied to the electrodes and the adjustment of the focusing action of the electron lenses through suitable control of the potentials 25 applied thereto.

We are aware of many physical modifications of our device and many other possible uses thereof that at once will be apparent to those skilled in the art. Our invention, therefore, is not to 30 be limited except insofar as is necessitated by the prior art and by the spirit of the appended claims.

We claim as our invention:

1. An electric discharge device comprising an 35 evacuated envelope, an electron-source, a secondary emitter-electrode, an accelerating electrode and a target electrode mounted in the order named within said envelope, said emitter-electrode being accessible to electrons from said 40 source and said accelerating and target electrodes being accessible to secondary electrons from said emitter-electrode, and a plurality of apertured electrodes serially disposed between said emitter and target electrodes for focusing 45 said secondary electrons upon said target elec-

trode, the apertures being substantially symmetrical with respect to a line drawn between said emitter, accelerating and target electrodes.

2. An electric discharge device comprising an 5 evacuated envelope, an electron source, a secondary emitter electrode and a collector-electrode mounted in spaced relation in the order named within said envelope, said emitter-electrode being accessible to electrons from said source and said collector-electrode being accessible to secondary 10 electrons from said emitter electrode, and means comprising an accelerating electrode and a plurality of electrically separate electron-lens elements mounted in the space between said emitter and collector-electrodes for directing the elec- 15 trons in their passage therebetween.

3. The invention as set forth in claim 2 and 20 wherein said electrically separate electron lens elements are of the electrostatic type and wherein in said accelerating electrode is mounted intermediate two of said electrostatic electron lens elements.

4. An electric discharge device comprising an 25 evacuated envelope, a plurality of electrodes capable of secondary emission mounted in spaced relation within the envelope and means comprising an accelerating electrode and a plurality of electron lens elements mounted in the space between two adjacent secondary emitter electrodes for guiding secondary electrons from one 30 electrode to the other electrode of the pair.

5. An electric discharge device comprising an 35 evacuated envelope, a plurality of electrodes capable of secondary emission and an output electrode mounted in spaced relation in said envelope, an accelerating electrode and a plurality of electron lens elements mounted in the space between two adjacent secondary emitter electrodes for directing electrons therebetween, and a second accelerating electrode mounted in the 40 space adjacent said collector electrode for drawing the electrons from the preceding secondary emitter electrode thereto.

GEORGE A. MORTON.
LESLIE E. FLORY.
